TROT LINE HOLDER AND SETTER

Edgar E. Vanderhider and John A. Wentreek,
Taylor, Tex.; said Wentreek assignor to Frank
W. Urbis, Taylor, Tex.

Application July 28, 1934, Serial No. 737,443

4 Claims. (Cl. 43—31)

This invention relates to a trot line holder and setter, namely, a device for holding a trot line in compact condition when not in use with the hooks in guarded condition and in proper position to be released, and whereby the hooks may be released in proper order and the line also released portion by portion in setting it for use in the water.

The main object of the invention is to provide a simple, reliable and efficient construction of holder of the character described with which the hooks may be readily engaged to hold the line in compact shape for storage and transportation with the hooks guarded and protected from injury thereto or to the person handling or carrying the holder.

A further object of the invention is to provide a holder of novel construction which facilitates the engagement therewith and disengagement therefrom of the hooks and in which the holder proper may, if desired, be economically made of a single piece of sheet metal.

The invention consists of the features of construction, combination and arrangement of parts, hereinafter fully described and claimed, reference being had to the accompanying drawing, in which:—

Fig. 1 is a perspective view of the holder illustrating its mode of use for holding a trot line.

Fig. 2 is a side elevation thereof with a portion broken away and in section.

Fig. 3 is an end elevation of the holder.

Fig. 4 is a plan view of the blank from which the holder body is made.

In carrying our invention into practice we provide a trot line holder and setter 1 comprising an elongated channelled body which is substantially of inverted U-shape in cross-section and consists of a top wall 2 and depending side walls 3, which side walls 3 are provided with longitudinally extending flange extensions 4 at their lower edges. These flange extensions 4 are bent upwardly from the lower edges of the walls 3 so as to lie within the channel of the body. As shown particularly in Fig. 3, the flanges 4 terminate below the top wall 2 and project upwardly and inwardly at oblique angles from the side walls, so that said flanges converge upwardly and inwardly with relation to each other to provide a space or passage between them. The upper free edges of the flanges are brought by the converging relation of the flanges to lie a short distance apart, so as to provide a guide slot 5 between them and the arrangement of the flanges is such as to form longitudinally extending pockets or chambers 6

between the same and the side walls 3. At one end of the holder the wall 2 is provided with a depending portion 2a which forms an end wall or closure for that end of the holder channel, while at the opposite end the channel of the holder is open and the side walls 3 at such end of the channel are cut away, as at 7, at an upward or inward angle, such cut away portion exposing the adjacent ends of the flanges 4 at that end of the holder to enable the same to be clearly observed and to facilitate the introduction and removal of the hooks upon the trot line. The top wall of the holder has secured thereto a suitable hand grip or handle 8, preferably of loop shape, whereby the holder and line may be conveniently carried and manipulated.

The trot line 9, a portion of which is shown, is provided at intervals in the usual manner with branches or leaders 10 which carry the fish hooks 11. When the line is not in use it may be disposed compactly in loop form, as shown in Fig. 1, and supported in depending position from the holder by engagement of the hooks 11 with the flanges in the channel of the holder, so that while the line will be supported, so as to be conveniently hung up or carried or manipulated while being set out, the hooks carried by the leaders will act as line supporting elements which are disposed in the channel of the holder and concealed and protected from injury thereto as well as guarded so as to prevent their exposure and injury to persons who might otherwise come in contact therewith.

In disposing the line for support from the holder the hook of the leader at one end of the line is first positioned as shown in Fig. 3 at the oblique end of the holder so as to be inserted into the passage between the flanges 4 and the guide slot 5, and the hook then slid inwardly toward the closed end of the holder, after which the hooks upon the succeeding leaders are successively introduced in the same manner until the hooks of all the leaders are thus disposed in the channel of the holder and engaged with one or the other of the flanges 4 thereof. When this work is completed the leaders 10 will depend vertically from the holder and the line will be disposed compactly in the form of accordion loops, in which condition the line or the leaders may be bound to maintain the line in compact position and prevent its displacement from the holder and to enable the line to be conveniently stored or transported. When the hooks are thus disposed, it will be seen that the shanks of the hooks will lie in the passage between the flanges, while the bights of the

hooks will extend through the guide slot 5 into the top of the channel and the barbed free ends of the hooks will depend and be housed in one of the pockets or channels 6 and supported by engagement with the contiguous flange member. 5 In this position the hooks will be guarded from external injury and coming in contact and causing injury to the person or clothes of a fisherman or others carrying or manipulating the holder. When it is desired to employ the line, 10 it may be conveniently transported to a boat, if not in position in the boat, and the line then set out where desired by successively sliding the hooks of successive leaders out of the channel at the open end of the holder, baiting each individual hook as removed and then dropping the related portion of the line or leader into the water. The 15 convenience with which this may be done, as well as the convenience in storing away the line again when desired, will be fully and clearly understood by those versed in the art without a further and extended description.

In practice, and as disclosed, the holder 1 may be readily and inexpensively made of a single 25 piece of sheet metal from a blank 1a of the form shown in Fig. 4, in which the portions of the blank which form the walls of the holder are numbered to correspond with the walls. In producing the 30 holder from the blank the blank is simply bent, by suitable means, along the dotted indicating lines, so as to produce the completed article.

From the foregoing description, taken in connection with the accompanying drawing, it will be seen that our invention provides a simple, inexpensive and convenient type of trot line holder 35 affording manifold advantages in the storing, setting and handling of trot lines. While this particular construction of holder is preferred, it will, of course, be understood that changes in the form, proportion and details of construction of the 40 holder falling within the scope of the appended claims may be made without sacrificing any of the advantages of the invention.

What we claim is:—

1. A trot line holder comprising an elongated channeled body of approximately inverted U-shape in cross-section and having longitudinally extending flanges at the lower ends of its side walls bent upward into the channel thereof and forming individual hook supporting flanges and a guide slot for the introduction and removal of the hooks between the flanges. 5

2. A trot line holder comprising an elongated 10 channeled body of approximately inverted U-shape in cross-section and having longitudinally extending flanges at the lower ends of its side walls bent upward at an angle in converging relation to each other into the channel thereof and forming individual hook supporting flanges and a guide slot for the introduction and removal of the hooks between the flanges. 15

3. A trot line holder comprising an elongated 20 channeled body of approximately inverted U-shape in cross-section and having longitudinally extending flanges at the lower ends of its side walls bent upward into the channel thereof and forming individual hook supporting flanges and a guide slot for the introduction and removal of 25 the hooks between the flanges, one end of said body terminating inwardly of the adjacent ends of the flanges to expose the latter.

4. A trot line holder comprising an elongated 30 channeled body of approximately inverted U-shape in cross-section and having longitudinally extending flanges at the lower ends of its side walls bent upward at an angle in converging relation to each other into the channel thereof and forming individual hook supporting flanges and 35 a guide slot for the introduction and removal of the hooks between the flanges, one end of said body terminating inwardly of the adjacent ends of the flanges to expose the latter. 40
